Nelson W. Howard

UNITED STATES PATENT OFFICE

GEORGE C. THOMAS, OF SWAMPSCOTT, MASSACHUSETTS, ASSIGNOR TO FITZ-EMPIRE
DOUBLE PIVOT LAST COMPANY, OF AUBURN, MAINE, A CORPORATION OF MAINE

HINGED LAST

Application filed October 25, 1922, Serial No. 596,867. Renewed October 9, 1930.

This invention relates to collapsible lasts, and is illustrated as embodied in an impositive lock last, that is, a last which can be collapsed by pressure alone but which offers 5 to collapse a definite and increasing resistance over a short distance from extended position. It has been proposed to provide the resilient structure required to permit the yielding resistance by means of a resilient hinge- or 10 abutment-pin, which is deformed or bent by the stresses incident to collapse (or extension). Two practical solutions of the problem have been provided by H. W. Lucas and myself, which are described and claimed in 15 our applications, Ser. No. 514,722, filed Nov. 12, 1921, and Ser. No. 516,194, filed Nov. 18, 1921, respectively. It is an object of this invention to improve still further the constructions provided by the two prior inventions 20 noted.

Accordingly, a principal feature of the invention resides in a novel organization comprising a resilient hinge or abutment pin located in the joint between the toe and heel 25 parts of a collapsible last, and an inextensible arched link connecting the parts, the center of the arch extending over and clearing the resilient pin.

This and other features of the invention 30 comprising certain combinations and arrangements of parts will be understood from the following description of a preferred embodiment thereof selected for purposes of illustration and shown in the accompanying 35 drawings, in which—

Fig. 1 is a partly sectional elevation of the last, and

Fig. 2 is a perspective view of the novel pin.

40 The heel part 10 and forepart 12 are separated by a cut conveniently formed to permit the use of an abutment pin or bearing pin between the last parts. As shown, it consists 45 of a V slot 14 in the top of the last and a short vertical cut 16 running from the bottom of the last to the apex of the V. A hole 18 is bored transversely through the last along the apex of the V cut to accommodate the bearing-, hinge-, or abutment-pin 20, shown as a

hollow tube or cylinder split lengthwise along one side as at 22.

The last parts are held together by a link 24, of arch form, in order to permit it to extend over the pin, and anchored in the last parts by two hinge pins 26, 28, respectively. These pins are so situated that the line joining their centers, or the effective length of the link, passes substantially below the center of the pin 20 when the last is in extended position, and does not pass below this center when the last is collapsed, it being obvious that throwing up the heel part in collapse will raise this line. The arch link 24 is not resilient and does not bend or deform in the collapsing movement. The hinge pin 20 does collapse under the pressure exerted by the arch link as the line joining its ends moves toward the center of the pin 20, and the slot 22, which is preferably arranged at the upper or lower side of the pin, partially closes under the stress, as indicated in dotted lines in Fig. 1. The stiffness of the cylindrical pin in resisting this compression supplies the resilient resistance to the initial collapsing movement which is desired. The pin can, of course, be designed to work without being slotted; all that is necessary being that it be compressible, and offer a substantial resistance to such compression. The mechanism illustrated is 70 very simple, compact and strong.

The amount of distortion of the pin is measured by the separation of the two arcs 30, 32, the former being swung about the center 36 of the pin 20 and the latter about the center of the pin 26. The design is such that the angle of the cut 14 in the top of the last is not greater than the angle 34—36—28. This will insure the parts remaining tight at all times.

It will be obvious that the novel pin disclosed can be used in any of the positions shown in the disclosures of the applications above cited, and the terms "hinge pin" or "abutment pin" are to be read broadly enough herein to cover the meaning of the same terms in these applications.

Having thus described my invention, what I claim as new and desire to secure by Letters Patent of the United States is:—

1. A last comprising a forepart, a heel part, a single resilient abutment pin in the joint between the last parts and extending across the last and an inextensible link with its ends pivoted to the last parts and extending over the pin in an arch, the line joining the ends of the link lying below the center of the abutment pin, the said pin being deformable under pressure to effect a resiliently resistant initial collapsing movement.
- 10 2. A last comprising a heel part and a forepart, a single resiliently compressible bearing pin forming part of the joint between the last parts and extending from one side of the last to the other, and an inextensible hinge link arching over the pin and joining the last parts, the effective length of the link being less than the sum of the distances of its ends from the center of the pin, and said effective length lying below the said center when the last is extended.
- 15 3. A last comprising a heel part and a forepart, having their opposed faces provided with recesses, a split resilient tube arranged in said recesses, and a bonding member rigid in the direction of its length and pivoted to the heel part and to the fore part, said bonding member being formed to extend about said split resilient tube.
- 20 4. A hinge last comprising a fore part and a heel part capable of movement between an extended and a collapsed position, a bonding member having fixed pivotal connection with both of said parts, rigid in the direction of its length and arranged to permit the last parts to move from an extended to a collapsed condition or vice versa, and a split resilient tube forming the pivot connection between the two last parts and extending across the plane of movement of said bonding member, the bonding member being formed to extend about the split resilient tube so as not to interfere with the movement of the last from extended to collapsed condition or vice versa.
- 25 45 In testimony whereof I have signed my name to this specification.

GEORGE C. THOMAS.
